UNITED STATES PATENT OFFICE.

MIMI M. MEYER, OF OAKLAND, CALIFORNIA.

DESIGN FOR A BED-PAN.

45,946.

Specification for Design.

Patented June 16, 1914.

Application filed March 31, 1914. Serial No. 828,631. Term of patent 3½ years.

To all whom it may concern:

Be it known that I, MIMI M. MEYER, a citizen of the United States, residing in Oakland, county of Alameda, and State of California, have invented a new, original, and ornamental Design for a Bed-Pan, of which the following is a specification, reference being had to the accompanying drawings, forming part thereof.

Figure 1 is a perspective view of the bed

pan. Fig. 2 is a cross sectional view of the same.

I claim:

The ornamental design for a bed pan, as shown.

MIMI M. MEYER.

Witnesses:

H. B. NICHOLS,
JOHN H. HERRING.
